US00D912246S

(12) **United States Design Patent** (10) **Patent No.:** **US D912,246 S**
(45) **Date of Patent:** **** Mar. 2, 2021**

(54) **ENDOSCOPE CONNECTOR**(71) Applicant: **ERBE-USA, Inc.**, Marietta, GA (US)(72) Inventor: **Daniel G. Maurice**, Monument Beach, MA (US)(73) Assignee: **ERBE-USA, Inc.**, Marietta, GA (US)(***) Term: **15 Years**(21) Appl. No.: **29/667,080**(22) Filed: **Oct. 18, 2018****Related U.S. Application Data**

(62) Division of application No. 29/605,341, filed on May 25, 2017, now Pat. No. Des. 835,266, which is a division of application No. 29/548,911, filed on Dec. 17, 2015, now Pat. No. Des. 791,940, which is a division of application No. 29/485,448, filed on Mar. 19, 2014, now Pat. No. Des. 750,235.

(57) CLAIM

The ornamental design for an endoscope connector, as shown and described.

DESCRIPTION

FIG. 1 is a perspective view of an embodiment;
 FIG. 2 is another perspective view of the embodiment;

FIG. 3 is a front view of the embodiment;

FIG. 4 is a back view of the embodiment;

FIG. 5 is a top view of the embodiment;

FIG. 6 is a bottom view of the embodiment;

FIG. 7 is a left side view of the embodiment; and,

FIG. 8 is a right side view of the embodiment.

The dash-dot broken lines shown in FIGS. 1-7 that bound regions of the design including the shaded areas represent the bounds of the claim and form no part of the claimed design. The remaining dash-dash broken lines shown in FIGS. 1-8 illustrate portions of the endoscope connector and form no part of the claimed design.
